CAN PUNCTURING DEVICE

Filed Aug. 27, 1934

FIG. 3.

FIG. 4.

INVENTOR,
FRANK F. HOSMER,
BY *Martin P. Smith* ATTY.

UNITED STATES PATENT OFFICE

2,015,271

CAN PUNCTURING DEVICE

Frank F. Hosmer, Glendale, Calif.

Application August 27, 1934, Serial No. 741,562

2 Claims. (Cl. 164—120)

My invention relates to a can puncturing device and has for its principal object, the provision of a relatively simple, practical and inexpensive device that may be conveniently employed for puncturing one or more holes in the end of a can, for instance, cans containing milk, syrup or other liquids or semi-liquids or cans containing powdered or pulverized products.

A further object of my invention is, to provide a can puncturing device that may be easily and quickly adjusted so as to be conveniently used on cans of different sizes.

With the foregoing and other objects in view my invention consists in certain novel features of construction and arrangements of parts that will be hereinafter more fully described and claimed and illustrated in the accompanying drawing in which:

Fig. 1 is a perspective view of a can puncturing device constructed in accordance with my invention, with dotted lines showing a can in position to be punctured.

Fig. 2 is a longitudinal section through the center of the device and showing the same folded into closed position.

No. 3 is an enlarged cross section taken on the line 3—3 of Fig. 1.

Fig. 4 is a perspective view of a bolt that is utilized in connecting the two main parts of the device.

Referring by numerals to the accompanying drawing which illustrates a preferred embodiment of my invention, 10 designates one of the main members of the device which is preferably formed from strap metal and provided with a longitudinally disposed slot 11. One end of this member is bent laterally to form a foot or projection 12 that occupies a plane two or three degrees past a plane located at right angles or ninety degrees relative to the plane occupied by the body of member 10.

The foot 12 is bent two or three degrees past a plane at right angles to the plane occupied by member 10 in order that when the tool is folded for storage or placed in a sales package, the outer end of the prong carrying arm that is connected to strap 10 and which is hereinafter described, will spring or snap into position below the end of the foot so that the device will be retained in a compact folded condition as illustrated in Fig. 2.

Arranged for sliding movement on the front of member 10, is a plate 13 and formed therethrough, is a rectangular aperture 14 that is occupied by the squared shank portion 15 of a bolt

16. The squared shank portion 15 passes and is arranged to slide freely through slot 11 and that portion of the shank of the bolt beyond the squared portion is reduced in diameter and threaded as designated by 17 for the reception of a winged nut 18.

The construction just described provides means for readily adjusting the plate 13 lengthwise upon the member 10 and clamping said plate to said member in differently adjusted positions and such construction also prevents the plate 13 from rotating on member 10.

A conventional hinge 19 connects one end of plate 13 to a straight bar 20, preferably formed of strap metal and the length of this bar is such that when the plate 13 is moved to the upper end of slot 11 and bar 20 is folded against the front face of member 10, the free end of said bar is engaged and retained by the slightly inclined foot member 12 at the end of member 10, as illustrated in Fig. 2.

Arranged to slide freely upon bar 20, is an open loop 21 of metal and projecting at right angles from one end thereof, is a prong 22.

Adjacent to the free end of bar 20, a portion of the metal in said bar is pressed out to form a stud 23, which prevents the loop 21 from sliding off said bar.

In the use of my improved can puncturing device, member 10 is arranged in a vertical position with the foot member 12 engaging beneath the bottom of the can that is to be punctured.

Plate 13 is now moved vertically upon member 10 until it occupies a position just above the top of the can and said plate is locked to member 10 by tightening the winged nut 18.

Slide 21 is now adjusted longitudinally upon bar 20 until the prong is in position to puncture the top of the can at the desired point and as downward pressure is applied to the outer portion of bar 20, the prong 22 will be forced through the top of the can.

By partially rotating the can while it is engaged by the device, and properly manipulating bar 20, the prong 22 may be forced through the top of the can at two or more different points.

Inasmuch as the plate 13 is readily adjustable lengthwise of member 10, the device may be quickly set for use on cans of different heights and as slide 21 moves freely upon bar 20, the device may also be quickly and conveniently used on cans of different diameters.

The device may be folded so as to occupy comparatively little space when packed for storage or transportation and when so folded and with

the scale shank 15 of the bolt at the upper end of slot 11, the free end of arm 20 is pressed into position behind the foot 12, which acts as a keeper (see Fig. 2.)

5 Thus it will be seen that I have provided a can puncturing device that is relatively simple in construction, inexpensive of manufacture, capable of being conveniently used for puncturing the ends of cans of different sizes and said device 10 being very effective in performing its intended functions.

It will be understood that minor changes in the size, form and construction of the various parts 15 of my improved can puncturing device may be made and substituted for those herein shown and described without departing from the spirit of my invention, the scope of which is set forth in the appended claims.

I claim as my invention:

20 1. A can puncturing device, comprising a straight body member, one end of which is bent

to form a foot that occupies a plane a few degrees past a plane at right angles to the plane occupied by said body member, a plate arranged to slide lengthwise on said body member, means for clamping said plate to said body member in differently adjusted positions, a bar hinged to said plate, a can puncturing instrumentality carried by said bar and the free end of which bar when folded against the straight body member engages the inner face of the slightly inclined foot. 10

2. A can puncturing device, comprising a straight body member provided with a longitudinally disposed slot, a foot projecting laterally from one end of said body member, a plate arranged to slide freely on said body member, means passing 15 through said plate and slot for clamping said plate to said body member in differently adjusted positions, a bar hinged to said plate, and a can puncturing instrumentality on said bar. 20
